(57) **CLAIM**

The ornamental design for a fastener with asymmetrical
locking projections, as shown and described.

(**) **Term:** **15 Years**

DESCRIPTION

(21) **Appl. No.:** **29/597,500**

FIG. 1 is a perspective view of the first embodiment of a
fastener with asymmetrical locking projections showing a
series of asymmetrical projections oriented opposite from
that shown in FIGS. 8-14;

(22) **Filed:** **Mar. 17, 2017**

FIG. 2 is a left side view thereof;

(51) **LOC (11) Cl.** **08-08**

FIG. 3 is a right side view thereof;

(52) **U.S. Cl.**

FIG. 4 is a rear view thereof;

USPC **D8/387**

FIG. 5 is a front view thereof;

(58) **Field of Classification Search**

FIG. 6 is a top view thereof;

USPC D8/349, 382, 385, 387, 388, 397, 399

FIG. 7 is a bottom view thereof;

CPC .. F16B 23/00; F16B 23/0061; F16B 23/0007;

FIG. 8 is a perspective view of the second embodiment of a
fastener with asymmetrical locking projections showing a
series of asymmetrical projections oriented opposite from
that shown in FIGS. 1-7;

F16B 23/0015; F16B 23/0069; F16B

FIG. 9 is a left side view of the fastener shown in FIG. 8;

23/0084; F16B 25/0036; F16B 35/04;

FIG. 10 is a right side view of the fastener shown in FIG. 8;

F16B 35/06; F16B 35/041

FIG. 11 is a rear view of the fastener shown in FIG. 8;

See application file for complete search history.

FIG. 12 is a front view of the fastener shown in FIG. 8;

(56) **References Cited**

FIG. 13 is a top view of the fastener shown in FIG. 8; and,

U.S. PATENT DOCUMENTS

FIG. 14 is a bottom view of the fastener shown in FIG. 8.
